UNITED STATES PATENT OFFICE.

HERBERT A. BERKMAN, OF CHICAGO, ILLINOIS, ASSIGNOR TO ZIM MANUFACTURING COMPANY, A CORPORATION OF ILLINOIS.

TOOL FOR REMOVING SPRING SUPPORTS ON AXLES.

Application filed June 10, 1925. Serial No. 36,212.

To all whom it may concern:

Be it known that I, HERBERT A. BERKMAN, a citizen of the United States, residing in Chicago, county of Cook, State of Illinois, have invented a certain new and useful Improvement in Tools for Removing Spring Supports on Axles, and declare the following to be a full, clear, and exact description of the same, such as will enable others skilled in the art to which it pertains to make and use the same, reference being had to the accompanying drawing, which forms a part of this specification.

The present invention relates particularly to tools for forcing the spring-supporting posts out of the axles of automobiles into which they are fitted and has for its object to produce a simple and novel tool of this kind particularly adapted for use on Ford axles.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a side elevation of a fragment of a Ford axle to which my improved tool has been applied, preparatory to removing the spring-supporting post; Fig. 2 is a view looking toward the part shown in Fig. 1, from the right hand side of Fig. 1, the axle being in section; and Fig. 3 is a section taken approximately on line 3-3 of Fig. 1.

Referring to the drawing, 1 represents a heavy U-shaped yoke. On the free end of each of the arms of the yoke is pivoted a dog. Each dog consists of a U-shaped member 2 embracing the arm on three sides, namely the front and rear and the outer side. The two side members and the cross piece of each dog preferably lie in contact with the adjacent faces of the yoke member on which the dog is mounted, and each dog is pivoted to its supporting arm, as indicated at 4, toward the upper inner corner. The extreme upper outer corner of each arm of the yoke is rounded, as indicated at 5, to permit each dog to swing from a position in which it lies at right angles to its supporting arm, with its closed end engaged with the outer side of said arm, to a position, such as indi-

cated in dotted lines on the left hand side of Fig. 2. The dogs are made sufficiently long so that the inner ends or noses thereof project into the space between the arms of the yoke when the dogs lie at right angles to the arms as shown in full lines in Fig. 2 of the drawings. On the front or rear, or on both sides of the yoke are lugs 6 that limit the downward swinging movements of the inner ends of the dogs. The parts are so proportioned that when the dogs are swung until they engage with the stops or lugs, their inner edges 7 lie approximately in the planes of the inner faces or sides of the arms of the yoke; thus permitting the tool to be applied laterally to an axle having an extreme width or thickness slightly less than the width of the opening in the yoke.

A comparatively heavy screw 8 extends upwardly through the closed portion of the yoke, midway between and parallel with the arms.

In using the tool on a Ford axle, such as shown at A in the drawings, such axle being I-shaped and having its web thickened, as indicated at a, at the point where the spring supporting post B passes through the same; the inner ends of the two dogs are swung down so as to leave the opening in the yoke unobstructed, and the yoke is then moved upwardly from underneath the axle, with the two noses of each dog lying on opposite sides of the enlargement or boss a on the axle. The dogs are then swung into their horizontal positions so as to overlie the lower chord of the axle. Then, upon turning the screw 8, the upper end of the latter engages with the bottom of the post B, forcing the post upwardly out of the axle. After the post has been removed, the yoke is lifted slightly, so as to permit the dogs to be swung into their release positions, whereupon the yoke may be withdrawn from the axle.

It will thus be seen that I have produced a simple and rugged tool that may conveniently be applied to and removed from a Ford axle, for easily forcing a spring-supporting post out of its socket.

While I have illustrated and described with particularity only a single preferred form of my invention, I do not desire to be limited to the exact structural details thus illustrated and described; but intend to cover

all forms and arrangements which come within the definitions of my invention constituting the appended claims.

I claim:

- 5 1. A device of the character described, comprising a U-shaped yoke, a U-shaped dog embracing the free end of each arm of the dog with its open side directed inwardly, the dogs being pivoted to swing about axes at
- 10 right angles to the plane of the yoke, stops to limit the downward movement of the inner ends of the dogs, the closed ends of the dogs cooperating with the arms on which they are mounted to limit the upward swinging movements of the dogs to positions in which the dogs lie at right angles to said arms and project into the space between the arms, the inner ends of the dogs being shaped to lie approximately in line with the inner faces of
- 15 20 said arms when the dogs are engaged with said stops, and a screw extending through

the closed end of the yoke between and parallel with the arms thereof.

2. A device of the character described, comprising a U-shaped yoke, a dog mounted 25 on the free end of each arm of the yoke so as to be capable of swinging downwardly from a position in which it lies transversely of the arm and extends inwardly toward the opposite arm, a stop on each of the arms to 30 prevent the dogs from swinging upwardly past the aforesaid position, other stops on the arms for limiting the downward swinging movement of the dogs to positions in which they lie outside of the inner faces of 35 the arms on which they are mounted, and a screw extending through the connecting piece of the yoke between said arms and arranged parallel to said arms.

In testimony whereof, I sign this specification.

HERBERT A. BERKMAN.
